UNITED STATES PATENT OFFICE.

FREDERICK O. KILGORE, OF MINNEAPOLIS, MINNESOTA, ASSIGNOR TO KILGORE MANUFACTURING COMPANY, OF OLDTOWN, MAINE, A CORPORATION OF MAINE.

CUSHIONING DEVICE.

No. 889,619.

Specification of Letters Patent.

Patented June 2, 1908.

Application filed March 18, 1907. Serial No. 362,818.

To all whom it may concern:

Be it known that I, FREDERICK O. KILGORE, a citizen of the United States, residing in Minneapolis, in the county of Hennepin and State of Minnesota, have invented an Improvement in Cushioning Devices, of which the following description, in connection with the accompanying drawings, is a specification, like letters on the drawings representing like parts.

This invention relates to a cushioning device especially designed and adapted among other uses to be employed on automobiles as a shock absorber. For this purpose I employ two preferably cylindrical members movable one within the other, and one of which is designed to be connected with the car body and the other to the spring supporting the car body or it may be to the axle of the car. One of the cylindrical members is closed at its ends and is provided with a piston having its rod or stem extended through one head of its cylinder and connected with the other cylindrical member. Provision is made for the passage of air or other elastic fluid, from one side of the piston to the other, to form air cushions within closed chambers formed by the piston and the heads of its cylinder as the piston is moved in opposite directions.

The present invention has for its object to provide means for adjusting the cushion to cars having different spring power or strength of springs which support the car body, and this result may be accomplished by providing means for cutting off the passage of air from one side of the piston to the other at different portions of the stroke of the piston in opposite directions. In the present instance I have shown one method of accomplishing this result, and to that end the cylinder in which the piston is located is provided with one or more ports extended longitudinally thereof intermediate its ends and arranged as will be described so as to be closed at different portions of the stroke of the piston, so as to form closed air chambers of different capacity or size and thereby obtain a greater or less cushioning effect to adapt the cushioning device to springs of varying strength or elasticity on different automobiles or other vehicles. The port or ports in the cylinder containing the piston may be cut off by means of a jacket on said cylinder, said jacket being provided as herein shown

with a slot, groove or channel on its inner circumference and extended longitudinally thereof. The jacket referred to, is capable of being turned on its cylinder so as to cause the slot or channel to connect different ports or different portions of the same port, as will be described. Provision is also made for forming an anti-friction bearing surface for the closed cylinder, as will be described.

The apparatus has further provision for avoiding cramping or binding of the cylinders by movement of the car body laterally as will be described.

Figure 1 represents a sufficient portion of an automobile provided with a cushioning device embodying this invention, to enable it to be understood. Fig. 2, a longitudinal section on an enlarged scale of the device shown in Fig. 1, the parts being in their extended position. Fig. 3, a like view with the parts compressed. Figs. 4, 5 and 6, details to be referred to, Fig. 6 being a section on the line 6-6, Fig. 5, looking toward the right.

Referring to the drawing *a* represents one member or cylinder, which is open at one end for the reception of the member *b*, which latter is closed at its ends by the heads *c*, *d*, and contains a piston *e*, having its rod *f* extended through the head *c* and connected with the head *g* of the larger cylinder or member *a*. One member as *a* is designed to be attached to the body *h* of the vehicle and the other member *b* to the body-supporting spring *i*, or it may be to the axle of the vehicle.

The piston *e* reciprocates in the cylinder or member *b* and provision is made for forming a closed chamber between the piston and that head of its cylinder toward which it is moving, and for varying the size of said chambers so as to form elastic cushions of greater or less volume or size, according to the spring action of the vehicle, that is, when the vehicle is supported on short or stiff springs, and the spring action of the vehicle is short, the cushioning device is adjusted so as to obtain a long cushion; and when the spring action is considerable, the device is adjusted so as to obtain a short cushion. In other words, the cushioning device is capable of being adjusted so as to not interfere with or diminish the action of substantially long springs, and to increase the action of substantially short or stiff springs. In the present instance I have shown one construction for accomplishing this purpose. To this end, the

cylinder *b* is provided with a plurality of ports or openings in its body portion, and arranged longitudinally thereof intermediate the ends of the cylinder. In the present instance, the cylinder *b* is shown as provided with eight ports marked 10, 11, 12, 13, 14, 15, 16 and 17, which are arranged in two groups located on opposite sides of the longitudinal center of the cylinder. The ports 10, 11, 12 and 13 constitute one group, and the ports 14, 15, 16 and 17 the other group, and the ports in each group are arranged obliquely with relation to the axial line of the cylinder and substantially out of line with one another, and corresponding ports of both groups are arranged substantially in line with each other as clearly shown in Figs. 2, 3, 4 and 5.

Provision is made for connecting corresponding ports of both groups, so that the elastic fluid may pass from one side of the piston *e* to the other, and this result may be accomplished by providing the cylinder *b* with a jacket 20 loose thereon and having on its inner circumference a groove, slot or channel 21, which is adapted to connect corresponding ports in the cylinder by turning the jacket on said cylinder. For convenience, the ports 10, 17 may be designated the end ports, the ports 13, 14, the center ports, and the ports 11, 12, 15, 16 the intermediate ports. When the jacket 20 is turned so that the slot 21 occupies the position shown in Fig. 4, the portion of the cylinder *b* on one side of the piston *e* is connected with the portion on the opposite side of said piston, so that the air can pass from one side of the piston to the other through the end ports 10, 17, until one of the said end ports is closed by said piston, thereby forming a closed chamber behind the piston, which contains air, and further movement of the piston is resisted by a confined body of air, which forms an elastic cushion to absorb the jars or shocks occasioned by the vehicle traveling over rough roads. It will be observed that when the end ports 10, 17 are connected as represented in Figs. 2 and 4, the piston has its longest range of movement and that the air cushion is of minimum size or area. This condition is useful with vehicles having considerable spring action.

If the spring action is shorter than that above referred to, the jacket 20 is turned so as to close the end ports, and with the shortest spring action, all the ports are closed except the center ports 13, 14, which condition is represented in Fig. 5. By reference to Fig. 5, it will be seen that the piston *e* would have to travel but little distance before it closed one of the ports 13, 14, consequently forming a long or maximum air cushion behind it, so that in this case the action of the short spring is augmented by the long air cushion. If the spring action of the vehicle is between these limits, the jacket 20 is turned so as to uncover one or the other of

the intermediate ports 11, 16, or 12, 15, and thereby form an air cushion between the extreme air cushions above noted. In this manner the cushioning device may be applied to vehicles and especially motor cars having different spring power and adjusted to work in harmony with the spring power of the particular car to which it is applied. Furthermore this adjustment may be effected after the cushioning device has been applied to the car, thereby enabling one size of the device to be a standard for a number of cars having different spring action. It will be observed, that by adjusting the jacket the volume of fluid which is permitted to pass from one side of the piston to the other, may be varied according to the elasticity of the spring supporting the car body. In this manner, a too rapid action downward of an elastic spring or a too rapid recoil of such spring, can be retarded or restrained to obtain the desired spring action for comfortable riding. This feature is also useful when a non-elastic fluid is used. Provision is also made for preventing the members of the device being bound or cramped by sudden lurching or side movement of the car body, and for this purpose, the member *a* is connected with the car body by a ball and socket joint, which may be made as shown in Fig. 2, wherein the head *g* of the member *a* is shown as provided with a boss 30 having a substantially circular socket 31 provided with a lateral opening 32, and into which is extended a ball 34 attached to an arm 35, which is fastened to the car body. The socket 31 and the opening 32 are of greater diameter than the ball 34, and said socket is provided with a lining 36 of composition or other suitable antifriction material, which serves to retain the ball 34 in its socket. The member *b* is provided with a lug 40 having a ball and socket joint in a similar manner, and consisting of a ball 41 open at diametrically opposite points and retained in a socket in the lug 40 by a lining 42. Provision is also made for obtaining a substantially long antifriction bearing surface for the members *a*, *b*, to slide on. This result may be accomplished by providing the jacket or sleeve 20 with suitable openings in which are laid blocks or pieces 45 of anti-friction material, preferably non-metallic, which fill the space between the member *b* and the member *a* as clearly shown in Fig. 2.

I have herein shown one form of means for varying the length and volume of the air cushion to adjust it to cars of different spring power, but I do not desire to limit my invention to the particular construction shown.

I have herein described the invention as embodied in an apparatus employing air or other elastic fluid, which I prefer to use, but I do not desire to limit my invention in this respect, as certain features of the invention

may be embodied in apparatus employing a liquid, as for instance, the cylinder *b* having means for by-passing the liquid and additional means for regulating or controlling the volume or amount of the liquid so bypassed, may be used to advantage in a shock absorber employing a liquid. The piston *f* may be surrounded with a flexible dust-guard 50.

10 Claims:

1. In an apparatus of the class described, in combination, a cylinder closed at one end and open at its other, a second cylinder provided with heads and movable in the first-mentioned cylinder, a piston in said second cylinder having a piston rod extended through one of said heads and secured to the first-mentioned cylinder, ports or openings in said second cylinder arranged out of line with one another, a jacket loose on said second cylinder and provided with a groove or channel to permit of the passage of fluid from one side of the piston to the other, said jacket being movable on its cylinder to vary the length of 25 the fluid cushion formed between said piston and an end of its cylinder, substantially as described.

2. In an apparatus of the class described, in combination, a cylinder closed at one end 30 and open at its other, a second cylinder provided with heads and movable in the first-mentioned cylinder, a piston in said second cylinder having a piston rod extended through one of said heads and secured to the first-mentioned cylinder, ports or openings in said second cylinder arranged out of line with one another, and means to close said ports or openings to form closed chambers of different sizes or capacities between said piston and a 40 head of its cylinder, substantially as described.

3. In an apparatus of the class described, in combination, two members movable one 45 within the other, a piston in one of said members having its piston rod connected with the other of said members, means coöperating with said piston for permitting the passage of fluid from one side of said piston to the other, and for forming closed chambers at opposite 50 sides of said piston, and means for varying the size of said closed chambers to adjust the device to different spring action, substantially as described.

4. In an apparatus of the class described, 55 in combination, two members movable one within the other, a piston in one of said members having its piston rod connected with the

other of said members, means coöperating with said piston for permitting the passage of fluid from one side of said piston to the other, 60 and for forming a closed chamber between said piston and the end of its cylinder, and means for varying the size of the closed chamber, substantially as described.

5. In an apparatus of the class described, 65 in combination, two cylindrical members movable one within the other and one of which is provided with openings in it, a piston in one of said members having its piston rod connected with the other of said members, 70 and pieces of antifriction material inserted into the openings in one of said members and making contact with the other of said members, substantially as described.

6. In an apparatus of the class described, 75 in combination, two members movable one within the other, a piston in one of said members having its piston rod connected with the other of said members, means coöperating with said piston for forming closed chambers 80 at opposite ends of one of said members, and means for varying the length of said closed chambers, substantially as described.

7. In an apparatus of the class described, 85 in combination, a cylinder provided with ports or openings intermediate its ends, a piston in said cylinder coöperating with said ports to form closed chambers at opposite ends of the cylinder, and means coöperating with said ports to vary the length of said 90 closed chambers, substantially as described.

8. In an apparatus of the class described, 95 in combination, a cylinder provided with a plurality of ports on opposite sides of its center, a piston in said cylinder coöperating with said ports to form closed chambers at opposite ends of the cylinder, and means coöperating with said ports to vary the length of said closed chambers.

9. In an apparatus of the class described, 100 in combination, a cylinder provided with a plurality of ports on opposite sides of its center, a piston movable therein toward the opposite ends of said cylinder, and a sleeve loose on said cylinder to turn thereon and provided 105 with a groove to connect the said ports, substantially as described.

In testimony whereof, I have signed my name to this specification in the presence of two subscribing witnesses.

FREDERICK O. KILGORE.
